(57) **CLAIM**

I claim the ornamental design for the measuring tool, as shown and described.

DESCRIPTION

FIG. 1 is a first top perspective view of the measuring tool; FIG. 2 is a second top perspective view of the measuring tool opposite FIG. 1;

FIG. 3 is a first bottom perspective view of the measuring tool;

FIG. 4 is a second bottom perspective view of the measuring tool, opposite FIG. 3;

FIG. 5 is a top view of the measuring tool;

FIG. 6 is a bottom view of the measuring tool;

FIG. 7 is a front view of the measuring tool;

FIG. 8 is a rear view of the measuring tool;

FIG. 9 is a side view of the measuring tool;

FIG. 10 is a side view of the measuring tool showing the side opposite that shown in FIG. 9;

FIG. 11 is a top view of the measuring tool, on a reduced scale;

FIG. 12 is a top view of the measuring tool, on a reduced scale;

FIG. 13 is a top view of the measuring tool, on a reduced scale; and,

FIG. 14 is a bottom view of the measuring tool, on a reduced scale.

The broken lines showing of a rule in FIGS. 11-14 form no part of the claimed design. The other broken lines show portions of the measuring tool that form no part of the claimed design.

The “dash-dot-dash” broken lines define the bounds of the claimed design and form no part thereof.
